WEB SUPPLY MECHANISM

William C. Wicking, Woodhaven, N. Y., assignor
to R. Hoe & Co., Inc., New York, N. Y., a cor-
poration of New York

Application March 12, 1941, Serial No 382,859

17 Claims. (Cl. 242—75)

This invention relates to web supply mechanisms for machines, such as printing machines, adapted for printing newspapers, magazines, etc., and more particularly to improvements in such mechanisms whereby the web tension may be more efficiently controlled.

This invention contemplates as its principal object improvements in a web supply mechanism of the form shown in Patent Number 2,155,431, issued April 25, 1939.

Another object is to provide means to continuously move a member carrying a running belt or other web tension controlling device, toward an unwinding web roll at proper speed to compensate for tension variations that would result from the decrease in diameter of the roll as the web is drawn therefrom.

Still another object is to provide in means of the above defined nature, a variable speed device, and means whereby the speed thereof may be automatically changed as a web tension controlling member is being moved toward the web roll.

A further object is to provide electrically operated controls whereby the operation of the continuous drive for the member carrying the web tensioning belt or belts is interlocked with other devices adapted to operate upon the web, whereby a maximum of safety and efficiency in the operation of the entire mechanism will be assured.

It is also an object of this invention to provide a web supply mechanism of generally improved construction, whereby the same will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

Figure 1 is a side view of a web supply mechanism for a printing machine and embodying the features and principles of this invention;

Figure 2 is an enlarged side view of the drive means for controlling operation of the member carrying the tension controlling device; and

Figure 3 is a diagram of the electrical connections for the various devices of the mechanism and including the controls therefor, together

with a schematic showing of a side view of the web supply mechanism in normal running position:

The web supply mechanism selected to illustrate the features and principles of this invention is the same as the web supply mechanism shown and described in the specification of Patent Number 2,155,431, issued April 25, 1939, but with the improvements of this invention 10 incorporated in its structure. As fully shown and described in the patent specification mentioned, the web supply mechanism includes the usual machine frame members 11, 12 and 13, and brackets 14 secured upon the spaced apart vertical frame members 12 and in which the opposite ends of the shaft 15 of a web roll supporting reel 16 are journaled. The reel 16 is adapted, in this instance, to support a running and expiring web roll 17, and a replacement web roll 18, both of which are shown in web renewing position, the web roll 18 being in position for normal running after the web thereof has been connected to the web 19 shown running from the expiring web roll 17.

As in the aforesaid patent, a web joining device is provided to join the webs of the rolls 17 and 18, and this device comprises arms 21 and 22 which are commonly pivoted at 23 to a bracket 24, extending downwardly from the upper horizontal frame member 13. The arms 21 and 22 are adapted to be swung from an inoperative position (see Figure 3) to the operative position shown in Figure 1. Arms 21 carry a web deflecting brush 25 and arms 22 carry supplemental arms 26 supporting a web severing blade 27. After the arms 21 and 22 have been swung into the operative position shown in Figure 1, they may be manipulated by a hand lever 28, acting through a cable 29 and under the control of suitable electrical devices, to first press the running web 19 against the web roll 18 to join the webs together, and then to project the web severing knife 27 and sever the web running from the expiring roll 17, the web roll 18 then becoming the running roll from which the web 19 is fed to the machine.

The running web roll, be it 17 or 18, due to being mounted upon the reel 16, may be adjusted 50 to align the web sidewise by adjustment of the reel 16 axially, by an electric motor 31 acting through gearing in a gear casing 32, and the reel 16 may be rotated to position the web rolls by means of an electric motor 33 acting through gearing in a gear casing 34. The motors 31 and

33 are controlled by suitable electrical controls as hereinafter explained.

Means are provided by this web supply mechanism, to effect a uniform tension on the web 19 running into the printing machine, and they include, a swingable arm 35 having a roller 36, which is disposed in a loop in the web 19 between web guiding rollers 37 and 38, the web 19 leading from the running web roll 17 or 18 over rollers 39 and 41 to the roller 37, and from the roller 38, over a roller 42 to the printing machine. A web roll rotating and braking means forms a part of the web tensioning mechanism, and includes one or more web roll contacting belts 43, which are led around pulleys 50 carried on arms 40, which are pivotally supported on swingable arms 44. An electric motor 45 is provided to swing the arms 44 and thereby move the belts toward or away from the web roll and coiled springs 46 are arranged to bias the arms 40 so as to keep the belts under tension. The motor 45 is of the type wherein a speed reducing means is directly associated therewith, and has an electrically operated brake 47.

The motor 45 is drivingly connected to the belt arms 44 through a bevel gear 48 and a gear segment 49, to swing the belt arms to increase or decrease the wrap of the belts 43 about the web roll, and thereby increase or decrease the tension on the web 19 being fed to the machine. Suitable controls are provided for efficiently controlling the operation of the motor 45. The belts 43 carried by the arms 44 are driven slightly slower than the speed of the running web, by a machine driven shaft 51, which is connected by means of bevel gears 53 and 54 to a shaft carrying a pulley 52, over which the belts 43 are led.

The controls for the motor 45 include a pair of electrical switches 55 and 56 disposed in a casing 57 and adapted to be actuated by switch operating members 58 and 59. The members 58 and 59 are adjustably mounted on a reciprocable rod 61 connected by a link 62 to a lever arm 63. The arm 63 is secured to, and swingable with the lever arm 35. The arm 35, and with it, the arm 63, is swung when variations in the tension of the web 19 cause the loop supporting the roller 36 to lengthen or shorten the tension of a coil spring 64 being set to maintain the desired operating tension by an adjusting nut 65. Variations in web tension are thereby corrected as the motor 45 will be actuated in the proper direction to either raise or lower the arms 44 and decrease or increase the wrap of the belts 43 about the web roll.

As the web roll decreases in diameter, the wrap of the belts 43 thereon decreases, causing a decrease in web tension, and the arm 35 will swing to move the rod 61. When the rod 61 has moved a determined amount, the "more tension" switch 56 will be energized, and the motor 45 will immediately operate to lower the belt carrying arms 44 to cause increased wrap of the belts 43 about the web roll. Means is provided to prevent a hunting action being set up whenever either of the switches are being operated, and is shown diagrammatically in Figure 3. A motor driven cam controlled switch 66 is provided for this purpose, and is connected into the electrical circuit of the switches 55 and 56, whereby the energization of the motor 45 will be by timed impulses, rather than continuously. To prevent the arms 44 from being moved either upward and downward beyond the safe amount, an "up" limit

switch 67, and a "down" limit switch 68 are provided to stop the operation of the motor 45.

In accordance with the teachings of the aforementioned Patent 2,155,431, provision also is included to prevent the operation of the reel rotating motor 33 and the web tensioning motor 45 when the arms 21 and 22 are in operative position as shown in Figure 1, and during their operation to join the webs. The means for so doing includes switches 69 and 71 which are operable by movements of the arms 22 and hand lever 28, into operable position, and are arranged to be in control of the reel rotation and web tension motor circuits respectively. Other instrumentalities, such as the provision of manually operable means, herein shown as a handle 72, for adjusting the switch operating members 58 and 59, and means to time the web joining operation are the same as those shown in the hereinbefore mentioned specification.

In combination with the above features and elements, this invention includes the provision of press driven means to slowly rotate the bevel gear 48 to gradually swing the arms 44 downwardly and increase the wrap of the belts 43 on the web roll engaged thereby, in order to compensate for the decrease in the diameter of the web roll, as the web is being drawn therefrom.

While the motor operated means for controlling the motion of the arms 44 in response to movement of the roller 36, controls the tension on the web in a very satisfactory manner, the mechanism herein disclosed is a further advance in the art. The arms 44 are operated under normal conditions by a driving connection with the press which moves the arms downward very slowly but constantly while the press is running, and at a variable speed which increases as the web roll speed increases, due to its decreasing diameter. In normal operation, there is only a gradual motion of the arms, and this maintains an unvarying tension on the web, thereby avoiding even the minute variations that may be caused by an intermittent motion of the arms 44 when they are moved only by the motor 45 in response to the variation in tension that is reflected in a change in the position of the roller 36.

The means shown herein for continuously moving the arms 44 downwardly to increase the wrap of the belts 43 upon the web roll, includes an extension 73 on the shaft of the motor 45 having a member 74 of a magnetic clutch with its electrical contact rings 75 and 76 mounted and secured thereon. The other member 71 of the magnetic clutch is secured upon the end of a shaft 78 in operating alignment with the member 74.

The shaft 78 is extended through suitable bearings 79 and 81, and has a pair of adjustable and opposing sheave members 82 and 83 thereon. A belt 84 running between the opposing sheave members 82 and 83, cooperates with a pair of adjustable and opposing sheave members 85 and 86 on a shaft 87 shown mounted in bearings 88 and 89. The respective pairs of sheave members 82-83 and 85-86 are slidable axially upon the respective shafts 78 and 87 in the usual manner to vary their relative speeds, whereby they form a variable speed unit of the so-called "Reeves" type.

Simultaneous shifting of the pairs of sheaves 82-83 and 85-86 is effected by a system of levers 91, 92, 94 and 95, pivotally connected to collars on the shafts 78 and 87. The shaft 87 has a cone pulley 98 thereon, and is driven by

a belt 99 from a corresponding cone pulley 100 secured to a shaft 101 that is driven by a suitable connection (not shown) with any convenient rotating member of the machine.

The levers 92 and 94 are suitably fastened together for moving as a unit about a pivot 96. Similarly, levers 91 and 95 are fastened together to move as a unit about a pivot 97, and the levers 91 and 92 are connected by a slotted connection and pivot 93. It will be seen that downward movement of the lever 92 will move the sheave members 82-83 to separate them and decrease their effective diameter where engaged by the belt 84, and simultaneously the sheave members 85-86 will be moved toward each other and increase their effective diameter where engaged by the belt, this action resulting in increasing the speed of the shaft 78.

The means for automatically effecting the desired variation in the speed of the shaft 78 and through it the desired lowering speed of the arms 44, includes a cam 102 arranged to be rocked as the arms 44 are swung. The cam 102 is preferably secured to a shaft to which the arms 44 are secured, and has a roller 103 riding upon its periphery. The roller 103 is carried by a reciprocal rod 104 that is acted upon by a spring 105, reacting against a bearing block 106 for the rod 104, to constantly urge the roller 103 against the cam 102.

The arrangement of the parts of the automatically controlling means is such, that, as the arms 44 are lowered, the cam 102 acts on the roller 103 to raise it and the rod 104. This rod is pivotally connected to one end of a lever 107 pivoted at 108, the other end of the lever 107 being connected to one end of a link 109 that is preferably adjustable in length. The other end of the link 109 is connected to the outer end of the lever 92, and hence will move the lever 92 and adjust the variable speed unit by axially shifting the sheave members 82-83 and 85-86 when the arms 44 are moved. By manipulation of a threaded rod 111 secured to a lug 112 in one part of the link 109, and which is screw-threaded through a lug 113, secured to the other part of the link 109, a variation in the speed of the shaft 78 may be effected independently of the variation caused by the variable speed unit.

Variation in the thickness of paper will vary the number of revolutions a roll will make while being unwound, and consequently with a given machine speed, a roll of paper having twice the thickness of the paper of another roll, will become exhausted in one half the time. Cone pulleys 98 and 99 provide means for adapting the mechanism herein disclosed, to papers of various thickness dimensions. Obviously, this compensation can be effected by other means, such as change gears, or if still closer regulation is desired, a variable speed mechanism of the type hereinbefore described may be employed as a driving means between the shafts 101 and 87.

Under normal running conditions, the arms 44 will be swung at such a rate that the motor 45 will not be required to operate; but if for any reason, the tension on the web 19 should vary to such an extent that the motion of the roller 36 is sufficient to close either of the switches 55 or 56, the arms 44 will be swung by the motor 45 to increase or decrease tension as may be required to restore it to normal, after which the arms 44 will again be moved by the shaft 101.

Referring now to Figure 3, which shows the electric control devices and their circuits to-

gether with dotted line indications of the principal parts of the web supply mechanism, a coil 115 is arranged to actuate switches 114 and 116. This coil is preferably connected directly in parallel with the coil of a main motor control switch (not shown). If desired, however, the switches 114 and 116 may be operated by a direct mechanical connection with the main motor switch, such provision being made that the switches are closed when the motor switch is closed, and opened when the motor switch is opened. The switch 116 is connected by a conductor 117 to the magnetic clutch contact ring 75. A switch 118 actuated by a similar control coil 119 correspondingly arranged with respect to a switch (not shown) for the usual threading motor of the printing machine, is normally open, but if closed, would be connected to the contact ring 75 by the conductor 117. The other contact ring 76 is connected to the line wire L2. A conductor 121 leads from the switches 116 and 118 to and through normally closed switches 122 and 123 actuated by the "less tension" and "more tension" control coils 124 and 125 respectively for the tension motor 45. From the switch 123, the circuit continues through a conductor 126 to a normally closed switch 127 actuated by a coil 128. From the switch 127, the circuit leads through a conductor 129 to a normally closed switch 131 in association with the "up" limit switch 67, and with it, is adapted to be opened by the movement of the arms 44 into their extreme "up" position. From the switch 131 and by a conductor 132, the circuit continues to a normally closed switch 133 in association with the "down" limit switch 68, which with it, is opened by the movement of the arms 44 into their extreme "down" position in relation to the running web roll, such position being governed by the engagement of a switch 35 operating lever 134 with the now running web roll 18. The circuit continues from the switch 133, through a conductor 135 to and through normally closed switches 136 and 137 actuated by the forward and reverse control coils 138 and 139 respectively for the reel rotating motor 33. The switch 137 is now connected to the line wire L1.

It will be noted that when the machine is not running, the coils 115 and 119 are deenergized, the switches 116 and 118 are opened, and the clutch 74-77 will be released, even though all the other switches in the clutch energizing circuit are closed, but when either the main motor and control coil 115 or the threading motor and control coil 119 are energized, one or the other of switches 116 or 118 will be closed. The switches 122 and 123 however, are arranged to open and deenergize the clutch 74-77, when either of the control coils 124 or 125 for the tension motor 45 are energized, and the switches 136 and 137 in the same circuit, are arranged to open when either of the control coils 138 or 139 for the reel rotating motor are energized. The switches 131 and 133, also in the same circuit, are arranged to open whenever either of the associated arm movement limit switches 67 or 68 respectively are opened by movement of the arms 44 into their aforesaid extreme positions. The switch 127 is arranged to open to deenergize the clutch 74-77 when the coil 128 is energized. The coil 128 is energized when the web joining arms 21 and 22 are down in operating position as shown in Figure 1, the control switch 69 for this coil then being closed.

While the principal features of this invention

have been described above in relation to the various parts and devices fully shown and described in the aforesaid Patent 2,155,431, other control circuits are shown in Figure 3, which are not directly affected by the controls required for this invention. These additionally shown controls are fully described in the aforesaid patent and comprise generally control coils 141 and 142 for the web margin motor 31 and which are commonly connected to the line wire L1, and respectively connected to reel axial movement limit switches 143 and 144, which in turn are in series respectively with push button switches 145 and 146, whereby the motor 31 may be manually actuated to align the web margins.

In addition to the before-mentioned control coils 138 and 139 for the reel rotating motor 33, there is also provided means to energize these coils 138 and 139 including push button "forward" and "reverse" switches 147 and 148 respectively. The down contacts of the forward movement switch 147 are connected to the line wire L2, and through a coil controlled switch 149 to the forward control coil 138. From the coil 138, the circuit continues to the switch 71 actuated by the handle 28, and then through an emergency stop switch 151, controlled by a coil 152, to the line wire L1. The reverse movement switch 148 connects the coil 139 to the line wire L2, and from the coil 139, the circuit continues through the same path as does the forward control circuit. By passing through the switch 71, which is normally closed when the hand lever 28 is in inoperative position, the reel motor circuits are under its control and thus when a web join is to be made, the switch 71 is opened to prevent rotation of the reel 16 by the motor 33.

Preparatory to making a web join, the reel 16 is rotated to position the web roll 18, and the belt arms 44 are raised. These operations are accomplished by closing a push button switch 153 to energize switch closing coils 154 and 155. The circuit starting at the switch 153, which is connected to the line wire L2, continues to the coil 155, and thence to a switch 156, controlled by a coil 157, to the line wire L1. The coil 154 may also be connected to the line wire L2 through the push button switch 153, and is connected to a normally closed reel rotation limit switch 158. From the switch 158, this circuit leads through the switch 71 to the emergency switch 151, and thence to line wire L1. The coil 154 closes a circuit sustaining switch 159, the circuit of which may be opened by a normally closed push button switch 161.

Energization of the coil 155 will close a switch 162, whereby the arms 44 will be raised by the motor 45, and open the switch 149 to prevent operation of the reel rotating motor 33. Closing of the switch 162 will connect the line wire L1 to a switch 163 controlled by the coil 157. From the switch 163, the circuit continues to the tension motor control coil 124, and then to a switch 164 controlled by the coil 128. The switch 164 is connected to the line L2 by suitable connections (not shown), but in the control circuit of the reel rotating motor 33. Energization of the coil 124 actuates the motor 45 to raise the arms 44 to the limit, whereupon the limit switch 67 is opened to deenergize the coil 157. Deenergization of the coil 157 will open the switches 163 and 156, and also a switch 165, whereby the motor 45 will be stopped and the brake 47 set to hold the arms 44 in their "up" position. When the switch 156

is opened, it deenergizes the coil 155 thereby closing the switch 149 and energizing the coil 138, which starts the motor 33, and the reel is rotated thereby until the replacement roll reaches web joining position, when the motor is stopped by the limit switch 158. Various other controls, such as coil controlled switches 166, 167, 168 and 169, closed snap switches 171 and 172, push button switches 173 and 174, switches 175, 176 and 177, and a solenoid 178 are provided and are connected into the various circuits for control, timing and interlocking purposes as fully described in the specification of Patent 2,155,431.

As fully hereinbefore explained, means such as the magnetic clutch 74—77 is provided to connect the machine driven shaft 101 to the shaft extension 73 of the motor 45 to continuously lower the arms 44 as the web 19 is fed from the running web roll 17 or 18 during the operation of the machine. Means has also been provided to gradually increase the speed of the shaft 78 as the diameter of the web roll decreases. The means for so connecting the shaft 73 to the machine drive will be disconnected however, whenever the printing machine is stopped, the web tension motor 45 is energized, the web joining mechanism is in operative position, the belt arms 44 are at either their "up" or "down" limit position, or the reel rotating motor 33 is energized.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

40 What I claim is:

1. In a web supply mechanism, means to rotatably support a web roll from which a web is drawn and led into a printing machine, means to apply a braking action on the periphery of the web roll as it is rotated by the pull of the web, means driven in timed relation with the machine and acting normally to continuously feed the braking means toward the axis of the web roll as the roll decreases in diameter due to the web being withdrawn therefrom, and means controlled by web tension to move the braking means toward and away from the axis of the web roll.

2. In a web supply mechanism, means to rotatably support a web roll from which a web is led into a printing machine, means to apply a braking action on the periphery of the web roll as it rotates, means driven in timed relation with the machine and acting normally to continuously move the braking means toward the axis of the web roll as the roll decreases in diameter due to the web being withdrawn therefrom, and means to gradually increase the speed of movement of the braking means toward the web roll as its diameter decreases.

3. In a web supply mechanism, a rotatable support for a web roll from which a web is drawn and led into a printing machine, means to rotate the support to position the web roll, means movable to apply a braking action on the periphery of the web roll as it is rotated by the pull of the web, means driven in timed relation with the machine and acting normally to continuously move the braking means toward the web roll as the roll decreases in diameter due to the web being with-

drawn therefrom, means controlled by web tension to move the braking means toward and away from the axis of the web roll, and means to interrupt the movement of the braking means when the support rotating means is actuated.

4. In a web supply mechanism, means to rotatably support a web roll from which a web is led into a printing machine, means to apply a braking action on the periphery of the web roll as it rotates, means acting intermittently to adjust the braking means automatically when the tension on the web varies, means normally acting continuously to adjust the braking means as the roll decreases in diameter due to the web being withdrawn therefrom, and means to interrupt the action of the continuously acting adjusting means when the intermittently acting adjusting means is actuated.

5. In a web supply mechanism, a support for a web roll from which a web is withdrawn, a swingable arm, a running belt supported by the arm and adapted to be moved thereby into contact with the periphery of the web roll, a motor for swinging the arm, controls for the motor adapted to be actuated by variations in tension of the web being drawn from the web roll, to increase and decrease the effective contact of the belt on the roll, and means other than the motor to normally continuously swing the arm to maintain the belt in contact with the roll as the roll decreases in diameter due to the web being withdrawn therefrom.

6. In a web supply mechanism, a support for a web roll from which a web is withdrawn, a swingable arm, a running belt supported by said arm and adapted to be moved thereby into contact with the periphery of the web roll, a motor for swinging the arm, controls for the motor adapted to be actuated by variations in tension of the web being drawn from the web roll to increase and decrease the effective contact of the belt on the roll, means other than the motor to normally continuously swing the arm to maintain the belt in contact with the roll as the roll decreases in diameter due to the web being withdrawn, and means to gradually increase the speed of the continuously swinging means, as the diameter of the web roll decreases.

7. In a web supply mechanism, a support for a web roll from which a web is withdrawn, a swingable arm, a running belt supported by the arm and adapted to be moved thereby into contact with the periphery of the web roll, a motor for swinging the arm, controls for the motor adapted to be actuated by variations in tension of the web being drawn from the web roll to increase and decrease the effective contact of the belt on the roll, means to continuously swing the arm to maintain the belt in contact with the roll as the roll decreases in diameter due to the web being withdrawn, and means to interrupt the action of the continuously swinging means, when the said motor is actuated.

8. In a web supply mechanism, a support for a web roll from which a web is withdrawn, a swingable arm, a running belt supported by the arm and adapted to be moved thereby into contact with the periphery of the web roll, a motor for swinging the arm, controls for the motor adapted to be actuated by variations in tension of the web being drawn from the web roll to increase and decrease the effective contact of the belt on the roll to maintain a constant tension on the web, means operable separately from the motor to continuously swing the arm to normally maintain the

belt in contact with the roll as the roll decreases in diameter due to the web being withdrawn, and means actuated with the swinging of the arm to gradually increase the speed of the continuously swinging movement as the diameter of the web roll decreases.

9. In a web supply mechanism, means to rotatably support a web roll from which a web is led into a printing machine, a braking device acting on the periphery of the roll as it rotates, means driven in timed relation with the machine and acting normally to continuously move the braking device toward the periphery of the roll as the roll decreases in diameter due to the web being withdrawn, and means acting with movement of the braking device to gradually increase the speed of movement of the braking device toward the periphery of said web roll as its diameter decreases.

10. In a web supply mechanism for a machine operating on a web, a rotatable web roll support, a running belt adapted to engage a web roll on the support, a first means acting in response to variation in web tension to move the belt toward and away from the web roll to increase and decrease the wrap thereof upon the web roll and thereby control the tension of a web being drawn therefrom, a second means driven in timed relation with the machine to continuously move the belt toward the web roll to compensate for the decrease in diameter thereof as the web is withdrawn, and means to gradually increase the speed of the belt movement toward the axis of the web roll by the second means as the roll diameter decreases.

11. In a web supply mechanism, means to rotatably support a web roll from which a web is led into a printing machine, a braking device acting on the periphery of the roll as it rotates, means to apply the braking device, including means to continuously move the braking device toward the periphery of the web roll as the roll decreases in diameter due to the web being withdrawn, means to control the device moving means to gradually increase the speed at which the device is moved toward the periphery of said web roll as its diameter decreases, and other means to vary speed of movement of the device to compensate for variation in the thickness of webs of different web rolls.

12. In a web supply mechanism, a rotatable web roll support, a running belt adapted to engage a web roll on the support, a first means to move the belt toward and away from the web roll to increase and decrease the wrap thereof upon the roll to vary the tension of a web being withdrawn, a second means to normally continuously move the belt toward the web roll to compensate for the decrease in diameter thereof as the web is withdrawn, means to gradually increase the speed of the belt movement toward the web roll by said second means as the roll diameter decreases, and means to increase the speed of the increasing means to compensate for a variation in the thickness of webs of different web rolls.

13. In a web supply mechanism, means to rotatably support a web roll from which a web is fed into a printing machine, means to apply a braking action on the periphery of the web roll as it rotates, a first means controlled by the tension of the web as it is fed into the machine to quickly adjust the pressure of the braking means, a second means normally acting to continuously move the braking means toward the axis of the

roll at a continuously increasing speed as the diameter of the roll decreases due to the web being withdrawn therefrom, and means to prevent simultaneous action of both the first and second means.

14. In a web supply mechanism, means to rotatably support a web roll from which a web is fed into a printing machine, means to apply a braking action on the periphery of the web roll as it rotates, a first means controlled by the tension of the web as it is fed into the machine to adjust the pressure of the braking means, and a second means acting normally to continuously vary the action of the braking means as the diameter of the web roll decreases due to the web being withdrawn therefrom, and means to interrupt the actuation of the second means when the first means is actuated.

15. In a web supply mechanism having means to support a web roll from which a web is drawn into a printing or like machine, a brake means, means driven in timed relation with the machine and acting to move the brake means to maintain it in determined close contact with the periphery of the web roll as it rotates and a web is being drawn therefrom, and a variable speed driving device to progressively increase the speed of movement of the brake means toward the axis of the roll, to compensate for the more rapid change in diameter of the roll as the web is removed therefrom during operation of the machine.

16. In a web supply mechanism for a printing machine, a support for a web roll, a brake member adapted to engage the periphery of the roll, a brake applying means, first actuating means to actuate the brake applying means to slowly move the brake member relatively toward the axis of the roll at a continuous speed governed by the speed of the machine and to increase the speed of movement of the brake member in response to decrease in diameter of the roll, second actuating means acting in response to variation in web tension to actuate the brake applying means to quickly move the brake member relative to the axis of the roll, and means to prevent simultaneous action of both actuating means.

17. In a web supply mechanism for a printing machine, a support for a web roll, a brake member adapted to engage the periphery of the roll, a brake applying means, first actuating means to actuate the brake applying means to slowly move the brake member relatively toward the axis of the roll at a continuous speed governed by the speed of the machine, a variable speed driving device associated with the brake applying means to increase the speed of movement of the brake member in response to decrease in diameter of the roll, and second actuating means acting in response to variation in web tension to actuate the brake applying means to quickly move the brake member relative to the axis of the roll.

WILLIAM C. WIEKING.
